UNITED STATES PATENT OFFICE.

WILLIAM B. WADE, OF RIDGEWAY, VIRGINIA.

VALVE MECHANISM.

No. 883,123.

Specification of Letters Patent. Patented March 24, 1908.

Application filed April 6, 1907. Serial No. 366,688.

To all whom it may concern:

Be it known that I, WILLIAM B. WADE, a citizen of the United States, residing at Ridgeway, in the county of Henry and State 5 of Virginia, have invented certain new and useful Improvements in a Valve Mechanism, of which the following is a specification.

This invention is a valve-mechanism especially designed for a furnace-door opener 10 of that kind comprising a steam-cylinder, and a piston working therein and operatively connected to the furnace-door.

The object of the invention is to provide a simple and reliable valve mechanism, together with means whereby such mechanism 15 may be operated by the foot of the fireman in order that his hands may be left free to handle the shovel.

In the accompanying drawings, Figure 1 is 20 a front elevation partly in section. Fig. 2 is a side elevation. Fig. 3 is a section of the valve mechanism drawn to an enlarged scale.

Referring specifically to the drawings, 5 denotes the front of the locomotive boiler, 25 and 6 is the fire-door thereon having the usual knuckles 7 to which the pintle 8 is made fast, the latter working in lugs 9 on the furnace-door. The lower end of the pintle has a crank 10.

Below the furnace-door is a steam cylinder 11 which is mounted on the furnace front in any suitable manner. A piston 12 works in the cylinder and has a rod 13 which is connected by a rod 14 to the crank 10, by means 35 of which the movement of the piston is made to rotate the pintle 8 and thereby open or close the door 6.

The valve mechanism for controlling the movement of the piston 12 comprises a casing 15 which is mounted on the furnace-front below the cylinder 11. The casing has a longitudinal port 16 open at both ends to receive exhaust pipes 17. The valve receives steam from the boiler through a pipe 18 which enters a port 19 extending through the valve casing to the port 16. On opposite sides of the port 19 are ports 20 and 21, respectively, which also extend through the valve casing to the port 16. The port 20 is 45 connected by a pipe 22 to one end of the cylinder 11, and the port 21 is connected by a pipe 23 to the other end of said cylinder. The valves are plugs which work in bores 24 extending across the port 16, and having 50 transverse openings adapted to be brought

in line therewith. One of such valves, indicated at 25, is located between the ports 19 and 20, and another valve, indicated at 26, is between the ports 19 and 21. Between the port 20 and the exhaust 17 is a valve 27, and between the port 21 and the exhaust is a valve 28. The stems 29 of the valves 25 and 27 are connected outside the valve casing by a crossbar 30, and the stems 31 of the valves 26 and 28 are connected by a cross-bar 32. The cross-bar 30 is connected to a lever 33 on one side of its fulcrum 34, and the cross-bar 32 is connected to said lever on the other side of its fulcrum. To one end of the lever 33 is connected a spring 35 for drawing said end down, and the other end of the lever is connected by a link 36 to a lever 37 pivoted at one end to the floor, and having at the other end a foot-pedal 38 which is normally held elevated by the spring 35.

The operation of the apparatus is as follows: In Fig. 1 the valves 28 and 25 are open, and the valves 26 and 27 are closed. With the valves in this position steam enters the right end of the cylinder 11 through the ports 19 and 16, valve 25, port 20 and pipe 22. The piston is thus driven toward the left end of the cylinder from which the exhaust takes place through the pipe 23, ports 21 and 16, valve 28 and exhaust pipe 17. The movement of the piston toward the left end of the cylinder, by reason of its connection with the door, closes the same. The valves are normally held in this position by the spring 35. To open the furnace-door the foot is placed on the pedal 38 which tilts the lever 33, causing its end to which the valves 25 and 27 are connected to rise, and the end to which the valves 28 and 26 are attached to lower, whereby the position of the valves will be reversed. Steam then enters the left end of the cylinder through the ports 19 and 16, valve 26, port 21 and pipe 23, and the exhaust from the right end of the cylinder is through the pipe 22, port 20, valve 27 and pipe 17. The piston then moves forwardly and opens the door. Upon removing the foot from the pedal, the lever 33 is restored to its normal position by the spring 35 which returns the valves to the position shown in Fig. 1, so that steam again enters the right end of the cylinder and exhausts from the left end, whereby the piston is caused to travel toward the left end of the cylinder and the door is closed. In order that the door may

be held open without keeping the foot on the pedal a catch 39 is provided for holding the same down.

I claim:—

5. The combination with a cylinder having ports at its ends, and a piston working in the cylinder, of a pair of inlet and exhaust valves for the respective ends of the cylinder, a lever, a connection between the lever and one 10 of said pair of valves on one side of its ful-

crum; and a connection between the lever and the other pair of valves on the other side of its fulcrum, and means for operating the lever.

In testimony whereof I affix my signature, 15 in presence of two witnesses.

WILLIAM B. WADE.
